UNITED STATES PATENT OFFICE.

HENRY SCHNACKENBERG, OF NEW YORK, N. Y.

FOLDING BOX.

SPECIFICATION forming part of Letters Patent No. 640,818, dated January 9, 1900.

Application filed May 22, 1899. Serial No. 717,699. (No model.)

To all whom it may concern:

Be it known that I, HENRY SCHNACKENBERG, a citizen of the United States of America, residing at New York, borough of Brooklyn, county of Kings, and State of New York, have invented certain new and useful Improvements in Folding Boxes, of which the following is a specification.

My invention has reference to improvements in boxes made of paper or similar flexible material from a single piece or blank, and has for its object economy in the cutting up of material, compactness for packing in transportation while in the condition of a blank not yet set up in the form of a box, and particularly the formation of a strong and durable box which can be set up with the greatest facility and in the least time. Heretofore in boxes of this character the body of the box—that is to say, the bottom, side, and end flaps—have been introduced into the box-form from below, thus retarding the operation of inserting the body of the box into the form and rendering the body of the box liable to slip downwardly out of the box-form, due to the weight of the contents when the box is opened. According to my present invention I so construct the blank that the body of the box can be folded or introduced into the box-form from above, thus facilitating the operation of forming a practical box and producing a considerably-stronger box than heretofore in all respects.

The nature of my invention will best be understood when described in connection with the accompanying drawings, in which—

Figure 1 represents a plan view of the blank from which the box is formed. Fig. 2 is an end elevation showing the first step in placing the body of the box within the box-form. Fig. 3 is a plan view of Fig. 2. Fig. 4 is an end elevation showing the second step, Fig. 5 a similar view showing the third step, Fig. 6 a sectional elevation showing the fourth step, Fig. 7 a longitudinal section showing the fifth step, and Fig. 8 a transverse section showing the last step, for introducing the body of the box into the box-form. Fig. 9 is a perspective view of a completed box. Fig. 10 is a side view of the blank, showing the manner of turning up the gummed tongue. Fig. 11 is a perspective view on an enlarged scale, showing the body

of the box partly introduced into the box-form.

Similar letters and numerals of reference 55 designate corresponding parts throughout the several views of the drawings.

Referring to the drawings, the letter *a* designates that portion of the blank which forms the bottom of the box and which is provided 60 with end flaps *b b* and with side flaps *c c'*. The blank is scored along the lines 1 1 and 2 2 or otherwise formed with such folding-lines that the end flaps *b b* can be turned upwardly about the lines 1 1 and 2 2 and the side flaps 65 *c c'* upwardly along the lines 1 2 and 1 2 to form the body of the box. The inner side flap *c'* forms a continuation or extension of the blank of the box-form *d*, which latter is scored or otherwise formed with folding-lines, 70 as at 3 3, 4 4, 5 5, and 6 6, so as to permit the blank to be folded into substantially rectangular shape and to form an underlapping tongue *e*, which is provided with a gummed surface, so as to hold the box-form together 75 in a usual manner. The blank *d* of the box-form is also provided with a flap forming the cover *f*, which is scored at 5 6 to enable the cover to be turned down and also at 7 7 at a proper distance from its outer edge to form 80 the front lap *g* when the portion beyond the score-line is turned downwardly. The blank of the box-form is furthermore provided with end laps *h h*, which can be turned about the lines 3 8 and 4 5. The score-line 3 4 in line 85 with the score-line 6 8 is the turning-line of the blank forming the body of the box about the upper and outer edge of the box-form. The particular form of the blank is shown in Fig. 1 of the drawings and need not be more 90 fully described here.

In making up the box the blank is first folded over on the lines 3 3, 4 4, 5 5, and 6 6 to form the rectangular box-form, the tongue *e* being pasted to the adjacent end of the 95 form, as shown in Figs. 2 and 3 of the drawings. This places the parts in the position best shown in Fig. 2, which represents an end view. The portion of the blank forming the body of the box is then turned downwardly and inwardly about the front edge 3 4 of the box-form, as shown in Figs. 4, 5, and 6 and also in perspective in Fig. 11. The downward movement of the body of the box

causes the end flaps *b b* and the side flaps *c c'* to be turned inwardly, and the body of the box finally takes the position shown in Fig. 6. The end laps *h* on the box-form are then 5 turned downwardly and inwardly about the lines 4 5 and 3 8, as shown in Fig. 7, and then the cover *f* and its lap *g* are turned downwardly to the position shown in Fig. 8, thus completing the box. The cover and its lap 10 may then be held to the box by means of a suitable ribbon, tape, or cord *i* in a usual manner.

Before inserting the body of the box into the box-form after the latter has been set 15 up, as shown in Figs. 2 and 3, the end flaps *b b* can be turned upwardly and inwardly, as shown in Fig. 4, and the side flap *c* also turned in the same manner, as shown in Fig. 5, and then the entire body can be turned from above 20 downwardly into the box-form.

I do not wish to restrict myself to the particular form or configuration of the blank shown in the drawings, as it is evident that the same will be changed according to the 25 shape of box desired.

It will be readily understood that as the body of the box is provided with four flaps the box-form is reinforced on all four sides, and consequently a strong and durable box 30 not liable to distortion is formed.

What I claim as new is—

1. A paper box comprising a form open at top and bottom and provided with a box-body adapted to fold into said form downwardly 35 from above and connected with said box-form along one of the top edges of said box-form, substantially as described.

2. A paper box comprising a box-form open at top and bottom and made in substantially 40 rectangular form and provided with a box-body having a bottom and side and end flaps; said box-body being connected with said box-form along one of the top edges of said box-form and adapted to fold downwardly and 45 inwardly into said box-form about said top edge, substantially as described.

3. A paper box comprising a box-form open at top and bottom and made in substantially 50 rectangular form and provided with end laps and a cover, and a box-body having a bottom and side and end flaps and connected with said box-form along one of its top edges and adapted to fold downwardly and inwardly 55 into said box-form about said top edge; said end laps on the box-form being adapted to be turned inwardly and downwardly and said cover to be turned downwardly to close the box, substantially as described.

4. As a new article of manufacture, the 60 herein-described blank for boxes; the same consisting of a sheet of suitable material, one of the longitudinal edges of which forms the lower edges of the front, rear and end walls of the bottomless box-form, said sheet being 65 provided with a longitudinal crease or score forming the upper edges of said front, rear and end walls of the bottomless box-form,

transverse scores forming the adjacent end edges of said walls and a flap projecting beyond the portion of the longitudinal crease or score forming the upper edges of the front wall for forming an additional flap and the bottom wall of the box, said first flap being provided with crosswise and longitudinal creases or scores for forming the front, rear 75 and end edges of the bottom wall, substantially as and for the purpose described.

5. As a new article of manufacture, the herein-described blank for boxes; the same consisting of a sheet of suitable material provided with a longitudinal crease or score forming the upper edges of the front, rear and end walls of the bottomless box-form, transverse scores forming the adjacent end edges of said walls, and a flap projecting beyond the portion of the longitudinal crease or score forming the upper edge of the front wall for forming an additional flap and the bottom wall of the box; said first flap being provided with 80 creases or scores for forming the front and rear edges of the bottom wall and being also provided with supplemental flaps projecting from the side edges of its central portion, and longitudinal creases or scores at the adjacent 85 ends of the supplemental flaps, substantially 90 as and for the purpose specified.

6. As a new article of manufacture, the herein-described blank for boxes; the same consisting of a sheet of suitable material, one of the longitudinal edges of which forms the 100 lower edges of the front, rear and end walls of the box, said sheet being provided with a longitudinal crease or score forming the upper edges of the said front, rear and end walls of the box, transverse scores forming the adjacent end edges of said walls, a flap projecting beyond the portion of the longitudinal crease or score forming the upper edge of the front wall for forming the bottom wall of the box; said flap being provided with crosswise 105 creases or scores for forming the front and rear edges of the bottom wall, and an additional flap projecting beyond the portion of the longitudinal crease or score forming the upper edge of the rear wall, said additional 110 flap being provided with a crosswise crease or score for contacting with the top edge of the front wall, substantially as and for the purpose specified.

7. As a new article of manufacture, the 120 herein-described blank for boxes; the same consisting of a sheet of suitable material provided with a longitudinal crease or score forming the upper edges of the front, rear, and end walls of the box, transverse scores forming the adjacent end edges of said walls, a flap projecting beyond the portion of the longitudinal crease or score forming the upper edge of the front wall for forming the bottom wall of the box; said flap being provided with 125 crosswise creases or scores for forming the front and rear edges of the bottom wall and being also provided with supplemental flaps projecting from the side edges of its central por- 130

tion, and longitudinal creases or scores at the adjacent ends of the supplemental flaps, and an additional flap projecting beyond the portion of the longitudinal crease or score forming the upper edge of the rear wall; said additional flap being provided with a crosswise crease or score for contacting with the top edge of the front wall, substantially as and for the purpose set forth.

10 8. As a new article of manufacture, the herein-described blank for boxes; the same consisting of a sheet of suitable material, one of the longitudinal edges of which forms the lower edges of the front, rear and end walls 15 of the bottomless box-form; said sheet being provided with a longitudinal crease or score forming the upper edges of said front, rear and end walls of the box-form, transverse scores forming the adjacent end edges of said 20 walls, a flap projecting beyond the portion of the longitudinal crease or score forming the upper edge of the front wall for forming an additional flap and the bottom wall of the box, said first-mentioned flap being provided 25 with crosswise and longitudinal creases or scores for forming the bottom and the front, rear and end edges of the bottom wall, and flaps projecting beyond the portion of the longitudinal crease or score forming the upper 30 edges of the end walls of the box, substantially as and for the purpose set forth.

9. As a new article of manufacture, the herein-described blank for boxes; the same

consisting of a sheet of suitable material provided with a longitudinal crease or score forming the upper edges of the front, rear, and end walls of the box, transverse scores forming the adjacent end edges of said walls, a flap projecting beyond the portion of the longitudinal crease or score forming the upper edge 35 of the front wall for forming the bottom wall of the box; said flap being provided with crosswise creases or scores for forming the front and rear edges of the bottom wall and being also provided with supplemental flaps 40 projecting from the side edges of its central portion and longitudinal creases or scores at the adjacent ends of the supplemental flaps, an additional flap projecting beyond the portion of the longitudinal crease or score for 45 forming the upper edge of the rear wall; said additional flap being provided with a crosswise crease or score for contacting with the top edge of the front wall, and flaps projecting beyond the portion of the longitudinal 50 crease or score forming the upper edges of the end walls of the box, substantially as and for the purpose described.

In testimony whereof I have hereunto set my hand in the presence of two subscribing 55 witnesses.

HENRY SCHNACKENBERG.
